United States Patent

Des. 242,351
Patented Nov. 16, 1976

242,351

SPRAYER

Tetsuya Tada, 1339 Nishi Takadomari,
Onoda-shi, Yamaguchi-ken, Japan

Filed Jan. 2, 1975, Ser. No. 538,122

Claims priority, application Japan Sept. 4, 1974

Term of patent 14 years

Int. Cl. D23—01

U.S. Cl. D23—17

FIG. 1

FIG. 4

FIG. 5

FIG. 2

FIG. 3

FIG. 1 is a front view of a sprayer showing my new design, the rear being a mirror image of the front view shown;

FIG. 2 is a plan view thereof;

FIG. 3 is a bottom view thereof;

FIG. 4 is a left side elevation thereof; and

FIG. 5 is a right side elevation thereof.

I claim:

The ornamental design for a sprayer, substantially as shown and described.
